UNITED STATES PATENT OFFICE.

CHARLES BAYER, OF NEW YORK, N. Y.

PIANO-FORTE DAMPER-ACTION.

SPECIFICATION forming part of Letters Patent No. 354,619, dated December 21, 1886.

Application filed September 17, 1886. Serial No. 213,773. (No model.)

To all whom it may concern:

Be it known that I, CHARLES BAYER, a citizen of the United States, residing at New York, in the county and State of New York, have 5 invented a new and Improved Piano-Forte Damper-Action, of which the following is a specification.

This invention relates to damper-actions for piano-fortes, and it more especially refers to 10 bearings of damper-cranks and the manner of attaching the same to the rail.

The invention consists in the improvements hereinafter more fully set forth.

In the accompanying drawings, Figure 1 represents a longitudinal front view of part of a 15 main action-rail with the damper-crank and bearings attached. Fig. 2 is a section at line $x x$, Fig. 1, at an enlarged scale. Fig. 3 is a side view of the bearing at an enlarged scale.

20 A represents the main action-frame, of any desired form and material.

B is the damper-crank or lifting-bar applied to said rail, which is provided with the usual lifting-arm controlled by the treadle. 25 (Not shown in the drawings.)

20 $b b$ are the pivots on which the crank or bar B turns. These pivots are carried by bearings C. Each of these bearings C, cast of a circular or square form, is provided at its face 30 with a socket, e , to receive the pivot b , or rather the cloth bushes entered within said sockets and receiving the pivots b through them. At the lower surface of the bearing a longitudinal square projection, n , is made, fitting into a longitudinal groove, m , made in the main rail A. The groove m extends the whole length of the rail. When the damper-crank has been fitted to the main action-rail the bearings C or its projection n can easily be 35 moved in this groove m in its proper place and

position, and are then fastened to the rail by screws $v v$.

The end of the cloth bushes entered within the socket e may be lapped downward partly around the projection n , to fill the groove m , 45 and thus obviate the necessity of making an exact fit of the projection n within the groove m , and at the same time allow for any slight irregularities in the casting.

The shank b' of the pivots b may be slightly 50 crooked, as shown in Fig. 2, to pass the corner of the main rail and allow the crank or bar B to come down upon its cloth or felt bearing w when at rest, free of any contact with the rail or any part thereof. By this arrangement no trimming of the bearing will be required. A plain groove corresponding about to the 55 size of the projection n is all that is required on the main rail, and the work and trouble of countersinking holes or gouging out any part 60 of the rail to gain clearance for the motion of the shank b' or for inserting or withdrawing the pivots b will be obviated, and whereby considerable work and expense in fitting will be saved. 65

What I claim is—

The combination of the main action-rail A, provided with a longitudinal groove, m , and the damper-crank or lifting-bar B, having pivots b , with the plate-bearing C, having 70 sockets e on its top face to receive suitable cloth bushes and the pivot b , and longitudinal square projection n on the under side to engage into the groove m in the main rail, substantially as described.

CHARLES BAYER.
